UNITED STATES PATENT OFFICE.

STEPHEN LANE, JR., OF ENGLEWOOD, NEW JERSEY.

DESIGN FOR ALE-PUMPS.

Specification forming part of Design No. 6,699, dated June 10, 1873; application filed May 16, 1873.

CASE A.

To all whom it may concern:

Be it known that I, STEPHEN LANE, Jr., of Englewood, county of Bergen and State of New Jersey, have invented a Design for Ale-Pumps, of which the following is a specification:

The nature of my design is fully set forth in the following description and annexed drawing.

A represents plates or slabs of marble, wood, or other suitable material, which are so arranged with relation to each other as to constitute a recess, having five sides of a regular octagonal prism, or, as it will be readily perceived, the recess may be composed of an indefinite number of sides or slabs without departing from the general appear-

ance, which is intended to be and is that of a portion of any regular polygonal prism.

I am aware that square and circular recesses have been made and are in existence, and I do not claim either, but my design consists in the geometrical figure above mentioned formed by the arrangement of the slabs at obtuse angles to one another; and

What I claim is—

The design for an ale-pump, substantially as described, and shown in the accompanying drawing.

STEPHEN LANE, JR.
